(57) **CLAIM**

The ornamental design for a grill handle as shown and described.

DESCRIPTION

FIG. 1 is a perspective view of a grill handle showing my new design.

FIG. 2 is a front view of the grill handle of FIG. 1.

FIG. 3 is a rear view of the grill handle of FIG. 1.

FIG. 4 is a left-side view of the grill handle of FIG. 1.

FIG. 5 is a right-side view of the grill handle of FIG. 1.

FIG. 6 is a top view of the grill handle of FIG. 1.

FIG. 7 is a bottom view of the grill handle of FIG. 1.

FIG. 8 is a perspective view of the grill handle of FIG. 1, shown in a condition of use; and,

FIG. 9 is another perspective view of the grill handle of FIG. 1, shown in a condition of use.

The broken lines in the drawings depict portions of the grill handle that form no part of the claimed design.
